UNITED STATES PATENT OFFICE.

JOHN A. DANN, WILLIAM F. DANN, AND ISAAC N. DANN, OF NEW HAVEN,
CONNECTICUT.

IMPROVED FOLDING CHAIR.

Specification forming part of Letters Patent No. 37,277, dated January 6, 1863.

To all whom it may concern:

Be it known that we, JOHN A. DANN, WILLIAM F. DANN, and ISAAC N. DANN, of New Haven, in the county of New Haven and State Connecticut, have invented a new and useful Army Camp Chair, which folds compactly and is easy to carry; and we do hereby declare that the following is a full and exact description of the same.

Said chair is made of oak or other strong, durable wood. The curved legs (marked B in the drawings) are twenty-two and three-fourths inches long, one and three-fourths inch wide, and three-fourths of an inch thick. The legs C are twenty-two inches long, otherwise same size as B. The arms A are shaped of a bent piece, as in the drawings, are twenty inches long, one and one-fourth inch wide, and three-fourths of an inch thick, riveted at each end, with a slot for the flat-headed bolt I to slide in. The standards of the back F are seventeen inches long, one and three-fourths inch wide at the bottom, and five-eighths of an inch at top, and three-fourths of an inch thick, and turn loose on the ends of the piece K. The back slats, D, are parts of a circle, four and a half feet in diameter, sixteen inches long, five-sixteenths of an inch thick—the top one one and three-fourths inch wide, the other two, one and one-half inch wide—and are let into the standards F from the front edge, glued and riveted. The rounds H are sixteen inches long, three-fourths of an inch in diameter, and fit tight in the holes of the

legs and riveted through the leg and round. The one marked H H passes loose through the inside legs, C, and the rivet is below the hole. The front cross-piece, E, is curved, as in the drawing, is seventeen and one half inches long, one and three-eighths inch wide, and three-fourths of an inch thick, with a pin turned at each end one and one-half inch long, which turns loose in the hole of the leg B, and is tight and riveted in the hole of the arm. These dimensions are given as proportions of the several parts, not confining the chairs to those sizes. The seat is made of good Brussels carpet, or other strong fabric, rolled on the pieces E and K and secured in any suitable manner.

Drawing No. 1 shows the chair open, as when used to sit on; Drawing No. 2, as when closed.

Manner of closing the chair: Bring the pieces E and K together with a jerk; to open it, place the right hand on the slat D, the left hand on the piece E; raise the right hand with a jerk, then distend both hands.

We claim—

The arrangement of the slotted arms A, the bolts I, and standards F, in combination with the legs B C, with the several parts operating substantially as and for the purpose specified.

JOHN A. DANN.
WILLIAM F. DANN.
ISAAC N. DANN.
